UNITED STATES PATENT OFFICE.

HERBERT K. TABLER, OF COLMAR, ILLINOIS.

WINDMILL-REGULATOR.

SPECIFICATION forming part of Letters Patent No. 678,061, dated July 9, 1901.

Application filed September 6, 1900, Serial No. 29,196. (No model.)

To all whom it may concern:

Be it known that I, HERBERT K. TABLER, a citizen of the United States, residing at Colmar, in the county of McDonough and State 5 of Illinois, have invented a new and useful Windmill-Regulator, of which the following is a specification.

This invention relates to windmill-regulators; and one of the principal objects of the 10 invention is to provide means for transmitting the motion from the pump-rod to the windmill connection and imparting a certain definite amount of throw to the windmill connection irrespective of the extent or amount of 15 throw of the pump-rod, thus adapting the improved mechanism to be applied to and used in connection with different constructions of windmills in which different throws of the pump-rod are employed. By making the windmill-regulator capable of universal adjustment in the manner above indicated the said 20 regulator may be applied to any windmill and to any part of the tower thereof and quickly adapted to and connected with the pump-rod and when set up will serve to automatically 25 throw the windmill into and out of operation, according to the amount of water contained within the main tank or reservoir. The regulating mechanism is associated with 30 and controlled by a float mounted within the reservoir or tank and suitably connected by operating devices with the regulator.

It is also an object of the present invention to construct the windmill-regulator in 35 such a manner as to render it convertible from a cam-operated device to a straight-lever-operating device, which feature of convertibility may be taken advantage of when the governor or regulator is applied to a pump- 40 rod having a certain amount of throw.

Another object of the invention is to provide, in connection with the operating-cam, a lever which is adjustably associated therewith, so that the length of the lever may be 45 increased or diminished in primarily setting up the apparatus.

Another object of the invention is to provide, in connection with a toothed draw-bar attached to the windmill connection and forming, in fact, a part thereof, holding and operating pawls of novel construction associated with tripping mechanism for throwing the

pawls out of engagement with the draw-bar, the pawls themselves being adapted, by reason of their form and arrangement, to assist 55 in throwing the tripping devices and releasing the draw-bar for the purpose of throwing the windmill into operation.

With the above and other subordinate objects in view, the nature of which will more 60 readily appear as the description proceeds, the invention consists in the novel construction, combination, and arrangement herein-after fully described, illustrated, and claimed.

In the accompanying drawings, Figure 1 is 65 a side elevation of a portion of a windmill-tower, illustrating a pump, pump-rod, tank, the windmill-regulator, the windmill connection, and the float-operated connections which influence the windmill-regulator. Fig. 70 2 is an enlarged side elevation of the windmill-regulator. Fig. 3 is a similar view looking from the opposite side. Fig. 4 is a plan view of the same, showing the pump-rod and pump-rod link in section. Fig. 5 is a side 75 elevation taken from the same side of the apparatus as Fig. 3 and showing the mechanism adjusted for converting the cam-operated device into a straight-lever connection between the pump-rod and draw-bar. Fig. 6 is 80 a view similar to Fig. 1, showing the manner of mounting the windmill-regulator adjacent to the well-platform.

Similar numerals of reference designate corresponding parts in all figures of the drawings. 85

Referring particularly to Fig. 1, 1 designates a pump of any ordinary construction, mounted at the base of a windmill-tower, having the usual upwardly-converging uprights 2, connected at intervals and suitable elevations by cross-beams 3.

4 represents the pump-rod, which extends from the piston-rod of the pump upward to the crank wheel or disk of the windmill, so 90 as to be operated thereby in the usual manner, and 5 denotes a tank or reservoir to receive the water as it is pumped by the windmill.

In order to throw the windmill-regulator 100 into and out of operation and correspondingly affect the windmill, I employ a float 6, arranged in the tank 5 and having a connection 7, extending to a bell-crank 8, mounted

upon a centrally - arranged transverse supporting-beam 9, connected with the windmill-tower at a point preferably overhead and out of the reach of persons standing on the well-
5 platform, the said bell-crank being also connected by cord or wire 10 with one arm 11 of a trip-lever 12, forming the primary element of the windmill-regulating mechanism.

The regulator comprises, essentially, a
10 frame or bracket 13, the lower portion of which is preferably provided with flanges 14, spaced apart to embrace the supporting-beam 9 and also provide grooved extensions forming guides 15 for a vertically-movable draw-
15 bar 16, the said draw - bar being further steadied and guided by grooved guides 17 at the upper end of the upwardly-extending portion of the bracket or frame 13 at a suitable distance above the supporting-beam 9.

20 The draw-bar 16 is provided at its upper end with an opening 18 to receive the pull-wire 19, which, together with the draw-bar 16, forms the windmill connection, to which rotation is adapted to be transmitted from
25 the reciprocating pump-rod 4 by the mechanism to be described. The draw-bar 16 is of cruciform shape in cross-section or provided with two sets of oppositely-extending flanges, so as to secure strength and lightness, and
30 the lower end thereof is provided with an opening to receive a stop-ring 20, which upon coming in contact with the guides 15 will prevent the further upward movement of the windmill connection. One of the flanges of
35 the draw-bar is provided with saw-shaped ratchet-teeth 21, so that the draw-bar forms a rack-bar which is adapted to be engaged by an operating-pawl 22 and a holding pawl or
40 detent 23, said pawls being arranged with the operating pawl or dog 22 above the holding pawl or detent 23.

The draw-bar-actuating mechanism comprises a cam-operating lever 24, one end of which is pivotally connected to a pump-rod
45 link 25, hung upon the pivot 26 of a pivot-plate 27, secured to the pump-rod 4. The opposite end portion of the lever 24 is adjustably fitted in a slotted opening 28 in a laterally-projecting lug or arm 29 on the hub or
50 pivot sleeve 30 of a cam 31, the lever being connected adjustably with the cam by means of a headed pin 32, which is fitted through an opening in the lug or arm 28 and held by means of a cotter-pin or other suitable fastener 33, the said pin being adaptable to any of a longitudinal series of openings 34 in the lever 24, thus providing for lengthening or shortening the distance between the fulcrum of said lever and the point at which it connects the pump-rod link. In this way the amount of throw of the draw-bar may be primarily regulated with respect to the amount of throw of the pump-rod, so that a predetermined number of throws of the pump-rod will
65 depress the draw-bar sufficiently to throw the windmill out of operation.

The cam 31 is mounted upon a stud-shaft

35, connected with the bracket 13, and as the cam is oscillated by the lever 24, as the latter is in turn vibrated by the pump-rod link carried by the pump-rod in its reciprocatory movement, said cam comes in contact with and operates against an antifriction-roller 36, journaled upon a pin or stud 37, carried by a pawl-operating lever 38, which is fulcrumed at 39 on the frame or bracket 13, adjacent to the extremity of the upwardly-extending portion thereof. The roller 36 is connected to said lever on one side of the fulcrum 39, while connected with the lever at the opposite side of its fulcrum is a pawl carrier or hanger 40, to which the operating pawl or dog 22 is pivotally connected by means of a pin or pivot 41. The pawl-carrier 40 comprises a stop shoulder or flange 42, against which the pawl 22 is adapted to strike and normally bear when in operation, as shown in Fig. 3, so that the pawl proper cannot swing outward away from the draw-bar without moving the carrier 40 with it. The holding-pawl 23 is similar in form and arrangement to the operating-pawl and is connected with a carrier 43, having a shoulder or flange 44 for limiting the outward movement of the pawl relatively to its carrier. The carrier 43 is pivoted at 45 to an arm 46 of the frame or bracket and is extended above said pivot or fulcrum, where it is provided at its upper extremity with a weight 47. This upwardly-extending arm of the carrier diverges or extends outward away from the draw-bar when the pawl carried thereby is in operative engagement with the draw-bar, as shown in Figs. 2 and 3. Each of the pawls 22 and 23 is provided with a tooth or shoulder 48 to engage the teeth 21 of the draw-bar, and each pawl is further provided with an outwardly-curving tailpiece 49, adapted under certain conditions to bear against the teeth 21 and prevent them from throwing the pawls upward with sufficient force to break or bend them. The operating-dog 22 is further provided with a laterally-projecting stop-pin 50, adapted when the pawl is thrown upward to come in contact with the dog-operating link, hereinafter referred to, which will cause the pawl to drop back to its normal position.

The trip-lever 12 is fulcrumed on a pin or stud 51, and fulcrumed upon the same pin or stud is a shipping-lever 52, said lever being pivotally mounted at a point intermediate its ends and having connected thereto at points equidistant from its fulcrum a pair of pawl-operating links 53 and 54, the link 53 connecting pivotally with the pawl-carrier 40 and the link 54 connecting pivotally with the upper arm or extension of the pawl-carrier 43. By connecting the shipping-lever with the pawl-carriers in the manner shown and described when the upper end of the shipping-lever is vibrated toward the draw-bar both the operating-pawl and the holding-pawl will be thrown out of engagement with the draw-bar, and in order to insure and facilitate the

stripping of the pawls the shipping-lever 52 is provided at its upper end with a weight 55, having a stop surface or shoulder 56, adapted when the weight moves inward to come in contact with the stop-pin 57 on the pawl-operating lever 38, thus holding said lever elevated above the cam 31, which latter may then continue its oscillations without affecting the lever 38, and consequently without operating the dog 22. At the same time that the weighted end of the shipping-lever is thrown toward the draw-bar the weighted end 47 of the carrier 43 is thrown in the opposite direction and also toward the draw-bar, and the said weights are so arranged with respect to the fulcrums of said members that the weights will pass the vertical planes of the fulcrums, and thus remain in a position of rest with the pawls inactive until the parts are again thrown into operation by the float rising in the tank and operating by means of the described connections on the trip-lever 12.

In order to prevent the lever 38 from moving upward too far, a spring-stop 58 is secured to the upper portion of the frame or bracket 13 and overlying the lever 38. In order to compensate for the slipping of the holding-pawl 23 past the teeth of the draw-bar as the latter descends, the operating-link 30 54 is provided with a slot 59 to receive the pivot-pin 60, carried by the shipping-lever 52.

The trip-lever 12 is mounted on the same fulcrum as the shipping-lever, and said trip-lever is provided with several arms, one of which, 61, carries a weight 62 to hold the same downward when the regulating mechanism is in operation, another arm 63 being extended in the opposite direction and offset or deflected laterally to provide for the attachment of a hand connection 64, extending downward within reach of an operator standing on the well-platform, who is thereby enabled to swing the trip-lever and trip the mechanism before it is operated upon by the float within the water tank or reservoir. Opposite the arm 11 the trip-lever 12 is provided with another arm 65 for the same purpose as the arm 11, but adapted to receive the connection 10 in case the tank and the float 45 should be arranged at the opposite side of the center of the windmill-tower, thereby enabling the float to operate with a pulling action on the trip-lever. In order that the trip-lever 12 may throw the shipping-lever, said trip-lever is provided with a laterally-extending lug or shoulder 66, which operates in contact with the lever 52, as shown in Fig. 2.

From the foregoing description it is thought that the operation of the regulator will be readily understood. As the water lowers in the tank or reservoir 5 the float moves downward and relaxes the connections between it and the trip-lever 12, whereupon the weighted arm of the trip-lever moves downward and causes it, together with the shipping-lever 52, to move toward the position shown in Fig. 2. In such movement of the shipping-lever the

pawl-carriers and pawls are moved into engagement with the toothed draw-bar, and the roller 36 on the pawl-operating lever 38 is at 70 the same time allowed to descend into engagement with the cam. As the pump-rod 4 reciprocates it imparts a vibratory movement to the lever 24, thereby oscillating the cam, acting upon the roller 36, vibrating the lever 38, and moving the dog 22 up and down, causing said dog or pawl to successively engage the teeth of the draw-bar until said draw-bar is forced downward sufficiently to throw the windmill out of operation, the holding-pawl 23 serving to prevent the draw-bar from moving upward as the operating-pawl is ascending to take a fresh hold upon the draw-bar. As long as the tank remains filled the pawl 22 will continue to move up and down, but 85 will no longer affect the draw-bar, as it will move in contact with the smooth untoothed portion 67 of the draw-bar. As soon as the water begins to lower in the tank, however, and the float to descend the connections are 90 drawn upon, with the result that the lever 12 will be rocked in the opposite direction, the weight-arm 61 moving upward, and the shoulder 66 serving to vibrate the shipping-lever in the same direction. Just as the upper 95 weighted end of the shipping-lever is moving toward the draw-bar and relieving the tension against the pawls 22 and 23 the draw-bar 16 begins to move upward and bears in a corresponding direction against the shoulders or 100 teeth 48 of the pawls, with the result that the pawls act through their pivotal connection with their carriers to thrust the carriers outward away from the toothed side of the draw-bar, and in this way the pawls assist in tripping the mechanism and throwing the weights 47 and 55 toward each other and toward the draw-bar until finally the pawls are thrown entirely out of engagement with the draw-bar, the latter being released and allowed to 105 move upward, thereby throwing the windmill into operation and allowing the pump to replenish the supply of water in the tank.

Where the regulator is to be coupled to a pump-rod having a short throw, the regulator 110 may be converted into a straight-lever-operating device, dispensing with the cam and some of its connections. In such event the cam-operating lever 24 is detached from the cam and is turned end for end and bottom side up 115 and applied as shown in Fig. 5; the lever being bolted to the pawl-operating lever 38, as shown in Fig. 5, by removing the bolt or pin 37, upon which the roller 36 is journaled, and reinserting said pin or bolt through its opening in the lever 38 and also through one of the holes in the lever 24 and applying a nut thereto, thus securing the two levers together. Said levers are further connected at another point by means of the fulcrum pin or bolt 68 120 of the upper pawl-carrier, and in this way the two levers are rigidly connected and incapable of relative movement. The outer end of the lever 24 is then pivotally connected to the

pump-rod link 25, and as the pump-rod reciprocates the motion thereof will be transmitted to the operating-pawl 22 by means of the lever connection 24 38.

5 Instead of arranging the mechanism of the regulator overhead the supporting-beam 9 for the regulator may be supported directly on the platform of the well, as shown in Fig. 6, and the draw-bar 16 may work up and down 10 through an opening in said platform. Where the mechanism is located adjacent to the platform, a special wooden connecting-link 69 will be employed, connected at one end to the cam-operating lever and at the opposite 15 end to the pump-rod 4 by means of an eye-plate or bracket 70, connected rigidly to the pump-rod, and a yoke 71, inserted through an opening in the eye-plate and having diverging terminal portions which are provided 20 with a series of vertically-alined holes 72, adapted to receive the upper end of the link 69, the said link and yoke being connected by any suitable fastening devices. By providing the yoke with several sets of holes in 25 the manner illustrated in Fig. 6 the link 69 and the mechanism of the regulator may be located at any desired distance from the pump-rod. The operation of the regulating mechanism will be precisely the same as that 30 referred to in the description of Figs. 2 and 3.

The outer surface or end surface of the cam 31 is described on the arc of a circle the center of which is to one side of the fulcrum of the cam, so that the said outer surface of the 35 cam is slightly eccentric, the curvature of the cam being such that after the roller 36 passes the rounded corner 73 of the cam and travels along the said outer or end surface 74 thereof the latter will act to slightly raise the 40 roller, and thus when the movement of the cam is reversed the roller will travel with greater freedom backward toward the corner 73 of the cam until it again comes in contact with and travels along the main operative 45 surface of the cam.

From the foregoing description it will be seen that I have provided simple and efficient means whereby the motion of the pump-rod 50 may be transmitted to the draw-bar or windmill connection, and at the same time provision is made for imparting a predetermined and limited amount of movement to the draw-bar or windmill connection irrespective of the length of throw of the pump-rod. In this 55 way the regulator is adapted to a variety of windmills and pump-rods having different lengths of stroke. It will also be seen that the regulator is controlled by a float which is in turn controlled by the water-level in the 60 receiving tank or reservoir, whereby the desired level of water will be maintained in such reservoir. It will further be seen that the regulator may be readily converted from a cam-operating device into a straight-lever-operating device with slight change.

65 From the foregoing it is thought that the

construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention. 70

Having thus described my invention, what I claim as new, and desire to secure by Letters Patent, is—

1. In a windmill-regulator, the combination with the pump-rod and windmill connection, 80 of means for transmitting motion from the pump-rod to the said connection, and for imparting a definite and uniform throw to the windmill connection irrespective of the extent of throw of the pump-rod. 85

2. In a windmill-regulator, the combination with the pump-rod, and a draw-bar connected with the windmill, of means for transmitting motion from the pump-rod to the draw-bar, and imparting a definite and uniform amount 90 of movement to the draw-bar irrespective of the extent of movement of the pump-rod.

3. In a windmill-regulator, the combination with the pump-rod, and a draw-bar connected to the windmill connection, of means for 95 transmitting motion from the pump-rod to the draw-bar, and means for imparting a predetermined and uniform movement to the draw-bar irrespective of the extent of throw of the pump-rod. 100

4. In a windmill-regulator, the combination with the pump-rod, and a draw-bar connected with the windmill, of means including cam for transmitting motion from the pump-rod to the draw-bar, and imparting a definite and 105 uniform throw to the draw-bar irrespective of the amount of throw of the pump-rod.

5. In a windmill-regulator, the combination with the pump-rod, and a draw-bar connected with the mill, of cam-operating connections 110 for transmitting motion from the pump-rod to the draw-bar, and imparting a definite and uniform throw to the draw-bar irrespective of the length of throw of the pump-rod.

6. In a windmill-regulator, the combination 115 with the pump-rod and windmill connection, of adjustable means including a pivoted cam for transmitting motion from the pump-rod to the said connection.

7. In a windmill-regulator, the combination 120 with the pump-rod, and a draw-bar connected with the windmill, of adjustable means for transmitting motion from the pump-rod to the draw-bar, and for imparting a definite and uniform amount of movement to the 125 draw-bar irrespective of the extent of movement of the pump-rod.

8. In a windmill-regulator, the combination 130 with a pump-rod, a draw-bar connected to the windmill connection, of adjustable means for transmitting motion from the pump-rod to the draw-bar, and for imparting a predeter-

mined and uniform movement to the draw-bar irrespective of the extent of throw of the pump-rod.

9. In a windmill-regulator, the combination with a pump-rod and a draw-bar connected with the windmill, of adjustable means, including a cam, for transmitting motion from the pump-rod to the draw-bar, and for imparting a definite and uniform throw to the draw-bar irrespective of the amount of throw of the pump-rod.

10. In a windmill-regulator, the combination with a pump-rod, a draw-bar connected with the windmill, of an adjustable cam-operating connection for transmitting motion from the pump-rod to the draw-bar, and for imparting a definite and uniform throw to the draw-bar irrespective of the length of the throw of the pump-rod.

11. In a windmill-regulator, the combination with a pump-rod, and a draw-bar connected with the windmill, of means for transmitting motion from the pump-rod to the draw-bar, said means comprising, in part, a pivoted cam, and a lever, one end of the lever being connected with the pump-rod and the other end adjustably connected with the cam.

12. In a windmill-regulator, the combination with a pump-rod and a draw-bar connected with the windmill, of means for transmitting motion from the pump-rod to the draw-bar, said means including a pivoted cam, and a lever, one end of which is pivoted to the pump-rod and the other end portion provided with a series of orifices to be engaged by a pin to couple it with the cam.

13. In a windmill-regulator, the combination with the pump-rod, and a draw-bar connected with the mill, of means for transmitting motion from the pump-rod to the draw-bar, comprising trip-pawls which operatively engage the draw-bar.

14. In a windmill-regulator, the combination with the pump-rod, and a draw-bar connected with the mill, of means for transmitting motion from the pump-rod to the draw-bar, comprising knuckle-jointed pawls which operatively engage the draw-bar and assist in tripping the operating mechanism.

15. In a windmill-regulator, the combina-

tion with the pump-rod, and a draw-bar connected with the mill, of lever connections for transmitting motion from the pump-rod to the draw-bar, trip-pawls operating in connection with the draw-bar, a shipping-lever connected with said pawls and adapted to be partially operated thereby, and float-controlled means for throwing the shipping-lever.

16. In a windmill-regulator, the combination with the pump-rod, and a draw-bar connected with the windmill, of a cam, a cam-operating lever connected with the pump-rod, a cam-operated lever and a pawl connected with said lever and adapted to coöperate with the draw-bar.

17. In a windmill-regulator, the combination with the pump-rod and the draw-bar connected with the windmill, of a cam-operated lever, a pawl carried thereby and coöoperating with the draw-bar, a roller mounted on the cam-operated lever, a cam operating upon said roller, and a cam-operating lever connected with the pump-rod.

18. In a windmill-regulator, the combination with the pump-rod, and a draw-bar connected with the windmill, of operating mechanism for transmitting motion from the pump-rod to the draw-bar, said mechanism including operating and holding pawls, a weighted shipping-lever connected with said pawls for simultaneously moving the same into and out of engagement with the draw-bar, and a weighted carrier for the holding-pawl adapted in conjunction with the weighted shipping-lever to hold the pawls out of engagement with the draw-bar.

19. In a windmill-regulator, the combination with the pump-rod and a draw-bar connected with the windmill, of operating mechanism for transmitting motion from the pump-rod to the draw-bar, comprising operating and holding pawls, a shipping-lever having a link connection with both pawls, and a float-controlled trip-lever coöperating with the shipping-lever.
